UNITED STATES PATENT OFFICE.

LEWIS J. FOWLER, OF LINCOLN, NEBRASKA.

REVOLVING REFRIGERATOR.

SPECIFICATION forming part of Letters Patent No. 630,044, dated August 1, 1899.

Application filed July 13, 1897. Serial No. 644,465. (No model.)

To all whom it may concern:

Be it known that I, LEWIS J. FOWLER, a citizen of the United States, residing at Lincoln, in the county of Lancaster and State of Nebraska, have invented certain new and useful Improvements in Revolving Refrigerators, of which the following is a specification.

My invention relates to improvements in refrigerators, and especially revolving refrigerators provided with glass sides, and has for its object to provide a polygonal refrigerator show-case in which the goods may be adjustably placed and made to revolve at a touch. This object I accomplish in the manner and by the means hereinafter fully described in detail, and particularly pointed out in the claims, reference being had to the accompanying drawings, in which like reference-letters indicate like parts in all the figures.

Figure 1 is a front elevation of my invention. Fig. 2 is a sectional view of same on line N O, Fig. 3. Fig. 3 is a sectional view of same on line P R, Fig. 1. Fig. 4 is a plan view of the base of the socket in the end of the shaft. Fig. 5 is a vertical sectional view of socket, pivot, collar, and ends of shaft and pipe. Fig. 6 is a plan view of the strap g. Fig. 7 is a side elevation of strap g and end of shaft. Fig. 8 is a plan view of base of pivot.

My invention consists of a hexagonal-shaped box G, resting on six casters and consisting of an upper and lower chamber H and H'. The upper chamber H forms the ice-box and has a door D on one side. On two sides, opposite each other, there is a small opening l through the floor of the upper chamber H into the lower chamber H'. Rising from the floor of said chamber H around said openings l and extending nearly to the top of said chamber H are metal partitions l', secured to the side walls of said chamber H and forming flues through which the warm air rises. The bottom of the upper chamber H is arranged to drain into a pan h', which has a small pipe h² projecting a short distance downward from the center. The pan h' is supported under the chamber H by a strap g, the ends h of which are secured to the bottom of the chamber H. The lower chamber H' is the cold-storage chamber, and its sides when desired may be of three thicknesses of glass with air-spaces between them, thus making the interior of the cham-

ber H' visible and at the same time increasing its efficiency as a cold-storage chamber. One of the sides is arranged to serve as a door 55 D'. A hollow shaft B receives the mouth of the pipe h² into its upper end, which enters a hole in the bottom of strap g and is supported by said strap g. A socket d, shaped like a Greek cross and exteriorly screw-threaded 60 complementary to the inside of the lower end of the shaft B, is screwed into the lower end of said shaft B. In the center of the bottom of the lower chamber H' is fixed a short piece of pipe C, which projects downward through 65 the bottom of the chamber H'. A pivot f, shaped exteriorly like the socket d, is screwed in the top of the pipe C or placed on top said pipe C, and a collar k is screwed onto the top of said pipe C, said collar k rising around said 70 pivot f. The lower end of the shaft B revolves within the collar k when the socket d is placed on the pivot f. The collar k serves to receive and retain the end of the shaft B in place and to prevent any water leaking 75 into the refrigerator in passing from the shaft B and into the pipe C. Thimbles c are placed on the shaft B and provided with set-screws e, by which the thimbles c may be held at any point on the shaft B. Arms s radiate outward from the thimbles c, and shelves a rest on said arms s, or instead of shelves a hooks or other appliances may be used.

The operation of my invention is as follows: The ice being placed in the upper chamber H 85 anything may be put in the lower chamber H'. The metal partition l' and open space l facilitates the admission of the cold air to the lower chamber H'. Owing to the pivot f and socket d and the fact that they are constantly damp 90 the shaft B revolves very easily and enables everything in the chamber H' to be readily come at, or, if desired, the revolution of the things placed in the chamber H' may be used to attract attention and advertise the goods. 95 As the ice melts the water drains off through the pipe h², the shaft B, and pipe C into an outside receptacle.

Having thus described my invention, what I claim as new, and desire to secure by Letters 100 Patent, is—

1. In a refrigerator, a hollow cylindrical shaft adapted to receive the waste-pipe of the ice-box into its upper end and provided at

- its lower end with a socket exteriorly open to the passage of water, a pipe fitting in and passing through the bottom of such refrigerator, a pivot resting on top said pipe, said 5 pivot permitting the passage of water and a collar surrounding the top of said pipe and said pivot, said collar adapted to receive the lower end of said shaft, substantially as shown and described.
10. 2. In a refrigerator, a casing, and ice-box in the top thereof, a series of rotatable shelves below said ice-box, a hollow cylindrical shaft to support said shelves and adapted to receive the waste-pipe of the ice-box into its upper 15 end and provided at its lower end with a

socket exteriorly open to the passage of water, a pipe fitting in and passing through the bottom of such refrigerator, a pivot resting on top said pipe, said pivot permitting the passage of water, a collar surrounding the 20 top of said pipe and said pivot, said collar adapted to receive the lower end of said shaft, substantially as shown and described.

In testimony whereof I affix my signature in presence of two witnesses.

LEWIS J. FOWLER.
